DESIGN FOR A DRESS

Samuel J. Goldfarb, New York, N. Y.

Application November 10, 1937, Serial No. 72,759

Term of patent 3½ years

To all whom it may concern:

Be it known that I, Samuel J. Goldfarb, a citizen of the United States and resident of New York city, in the county of New York and State of New York, have invented a new, original, and ornamental Design for a Dress, of which the following is a specification, reference being had to the accompanying drawing, forming a part thereof.

Fig. 1 is a front elevational view of a dress, showing my new design.

Fig. 2 is a rear elevational view of same.

Fig. 3 is an enlarged fragmentary view of a portion of the garment in the dot and dash area of Fig. 1.

The characteristic feature of my design resides in the combination of the disclosed blouse section with a skirt having lace trimmed stripes, as shown.

I claim:

The ornamental design for a dress, as shown and described.

SAMUEL J. GOLDFARB.
